FLOOR OILER OR WAXER

August Steigerwald, New York, N. Y., assignor to
Emily Clark, New York, N. Y.

Application April 3, 1935, Serial No. 14,420

1 Claim. (Cl. 91—39)

My invention relates to a floor oiler or waxer, that is, to a liquid dispensing apparatus for applying oil, wax or the like to a floor or other similar surface.

5 It is the principal object of my invention to provide a very simple device of the character indicated, which is relatively cheap to manufacture, serviceable in use and in which the flow of liquid may be controlled at will or shut off completely.

10 It is a further object to provide in a device of the character indicated a spreader pad so formed as to be reversible, whereby when one spreader surface wears out the pad may be reversed to obtain a new spreader surface.

15 Other objects and various features of invention will be hereinafter pointed out or will be apparent to those skilled in the art.

20 In the drawing which shows, for illustrative purposes only, a preferred form of the invention—

Fig. 1 is a front view in partial section of a floor oiler or waxer embodying features of the invention;

25 Fig. 2 is a vertical sectional view of the device shown in Fig. 1; and

Fig. 3 is an enlarged sectional view of a detail.

In said drawing 5 indicates generally a reservoir for containing a liquid to be spread, for example, floor oil or floor wax. The reservoir may have a flat top 6 and be provided with a filler opening which may be closed by a screw cap 7. The sides 8—8 of the reservoir preferably converge downwardly and the converging sides may be rigidly secured to a tube 9, as indicated at 30 10—10, so that the tube forms the bottom of the reservoir or a permanent closure therefor. The ends of the tube are preferably flattened out and closed, as indicated at 11.

40 Provision is made for conducting liquid from the reservoir to the tube and from the tube to the outside of the reservoir. In the form shown I provide a screw-threaded fitting 12, rigidly secured to the tube 9 as by soldering. The fitting 45 is provided with a bore 13, opening into the tube 9 and with a side opening 14 communicating therewith, the communication, however, being controlled by a valve 15, screw-threaded into the fitting 12 and providing either a complete closure 50 of the bore 13 or a partial closure thereof, whereby the quantity of the liquid discharged into the tube 9 may be accurately regulated at will. The stem 16 of the valve extends upwardly through a suitable gland or stuffing box and is provided 55 at the outside with a hand wheel or handle 17

for operating the valve, as will be understood. The tube is provided with passage means, preferably in the form of spaced openings 18—18 on the bottom, so as to discharge liquid to the outside of the tube and reservoir onto a spreader 5 pad, designated generally 19.

The spreader pad may be and preferably is formed of a pair of flat strips 20—20 of felt or the like extending upwardly, so as to embrace the sides of the tube and also a portion of the 10 reservoir, and extending downwardly so as to form a spreader surface 21 to engage the floor or other surface to be oiled or waxed.

The spreader pad 19 may be held in place by retainer flaps 22 of sheet metal, secured, as by 15 soldering, to the sides 8—8 upwardly from the bottom thereof. The retainer flaps 22—22 in the form illustrated are flexible and engage the outer sides of the strips 20—20, so as to securely hold the same in place and clamp them to the reservoir. Means, such as through bolts 23 having wing nuts 24 thereon, serve to draw the retainer flaps 22—22 toward each other and compress the strips, as will be understood. The degree of compression to which the strips are subjected will, to 25 a considerable extent, determine the rate at which liquid is conducted through the pad onto the spreader surface. However, the valve 15 will also serve to regulate the flow of liquid and may entirely cut off the flow of liquid. 30

The strips 20—20 are preferably apertured symmetrically in a transverse direction, that is to say, the openings 25—25 for the reception of the through bolts pass through the strip at the transverse center, so that, should the spreader surface 35 21 become worn or otherwise unfit for use, the strips 20—20 may be removed and reversed, so that the opposite edges will be positioned at the bottom and constitute the spreader surface.

The reservoir is provided with a suitable handle 40 26, whereby the device may be carried about and moved over the floor or other surface to be oiled or waxed.

The operation is simple. The liquid, such as oil, wax or the like, to be spread on a surface is 45 poured into the reservoir and the screw cap 7 put in place. The valve handle 17 may then be turned so as to open the valve to just the desired extent, so as to permit the desired steady flow of liquid from the reservoir into the tube 9 and 50 through the discharge openings 18—18 onto the spreader pad 19. The device is then moved over the floor or other surface with the spreader surface 21 in contact therewith. The oil or wax discharged onto the spreader pad 19 and conducted 55

thereby to the spreader surface 21 will then be evenly distributed over the floor or other surface. When the device is not in use the valve 15 may be turned so as to entirely shut off the flow of liquid from the reservoir to the spreader pad and thus there will be no waste of oil or wax and, since the reservoir is tightly closed, there will be no deterioration of the liquid being used.

The tubular construction forming the bottom 10 of the reservoir not only functions as a distributor for the liquid from the reservoir but serves also as a very effective stiffening means for the reservoir.

While the invention has been described in considerable detail it is to be understood that various 15 changes may be made within the scope of the invention as defined in the appended claim.

I claim:

In a device of the character described, a reservoir having end walls and downwardly converging

front and rear walls, a distributor tube secured 5 between the lower edges of said walls and forming the bottom of said reservoir, said tube having a valve opening in the wall enclosed within said reservoir and a plurality of discharge openings in the outer wall, a valve for regulating said valve opening and having a handle at the outside of said reservoir, a pair of sheet metal flaps secured at one edge respectively to the front and rear external walls of said reservoir substantially above 10 the bottom thereof and extending substantially below the bottom, clamping means engaging said flaps below said tubular bottom for drawing the free portions of said flaps toward each other to clamp porous spreader pads against the front and rear walls of said reservoir above the distributor tube and from end to end thereof and against each other below said tube.

AUGUST STEIGERWALD.
